UNITED STATES PATENT OFFICE

2,482,709

DEVICE FOR PREVENTING CINDER ERUPTIONS FROM BLAST FURNACES

Herbert G. Hard, Birmingham, Ala., assignor to Tennessee Coal, Iron and Railroad Company, a corporation of Alabama

Application March 30, 1948, Serial No. 17,997

5 Claims. (Cl. 266—32)

1

This invention relates to metallurgical blast furnaces and particularly to improved means for preventing cinder eruptions from blast furnace hearths.

In the usual blast furnace with which I am familiar, the refractory brickwork of the hearth is surrounded by an outer jacket of heavy steel plates and a water cooled jacket within the outer jacket. The upper edge of the water cooled jacket has an outwardly directed ledge which rests on the upper edge of the outer jacket and receives the cooling water connections. The tuyère jacket is supported on this ledge. The fit between the ledge and the tuyère jacket is often imperfect. Thus there is a plane of weakness through the furnace wall through which molten cinder can erupt and cause severe damage.

An object of the present invention is to provide an improved and simple device for preventing cinder eruptions between the tuyère jacket and the water cooled hearth jacket.

A further object of the invention is to provide a means which solidifies any cinder that reaches the plane of contact between the tuyère jacket and the water cooled hearth jacket and thus utilizes such material to effect a complete seal of the plane of weakness.

In accomplishing these and other objects of the invention, I have provided improved details of structure preferred forms of which are shown in the accompanying drawings in which:

Figure 1 is a vertical sectional view of a blast furnace equipped with an improved device embodying features of the present invention;

Figure 2 is an enlarged vertical sectional view of the device shown in Figure 1; and

Figures 3, 4 and 5 are enlarged vertical sectional views similar to Figure 2, but illustrating modified constructions of the device.

Referring more in detail to the drawings:

In Figure 1 there is shown at 10 a blast furnace which, except for the features of the invention, may be of any usual construction. The furnace hearth is designated 12 and comprises an outer jacket 13, a water cooled jacket 14 and brickwork 15, all of circular outline in plan. As best shown in Figure 2, the upper edge of the water cooled hearth jacket has a ledge 16 through which cooling water enters the jacket via connections 17. Ledge 16 rests on the upper edge of outer jacket 13 and supports the tuyère jacket 18. The latter jacket has a somewhat smaller outside diameter than the hearth jackets and its edge is spaced inwardly from the edge of ledge 16. Tuyère jacket 18 carries cooling plates 19.

2

The contact between ledge 16 and tuyère jacket 18 is likely to be imperfect since the contacting surfaces are not machined but remain somewhat irregular. With usual constructions gases and cinder sometimes escape through brickwork 15 and may then erupt through the imperfect contact and cause severe damage to the furnace. To prevent such occurrences in accordance with the present invention, a continuous annular flange 20 depends from the underface of tuyère jacket 18. Said flange is spaced inwardly from the edge of the tuyère jacket and fits between the outside of the brickwork and the inside of the water cooled hearth jacket closely within the latter. Any molten cinder that tends to escape from the hearth through the brickwork impinges on the inner face of flange 20 and must flow around beneath said flange. Such cinder is thus brought into contact with water cooled jacket 14 below the contact with the tuyère jacket. The water cooled jacket solidifies the cinder which thus furnishes a seal against further cinder eruptions from the hearth.

In the construction shown in Figure 2 the flange is welded to the underface of the tuyère jacket. In the modified construction shown in Figure 3, the flange, designated 21, is integral with the underface of the tuyère jacket, the construction otherwise being the same as that shown in Figure 2. In the modified construction shown in Figure 4, the flange, designated 22, is integral as in Figure 3 construction, but also contains a cooling water duct 23 connected with the cooling water connection to the water cooled jacket.

In Figure 5 I have shown a modified construction in which the tuyère jacket extends outwardly of the hearth jackets. In this construction the flange, designated 24, is secured to the inner face of the tuyère jacket and comprises a ring of right angle cross section. The vertical leg of the flange fits closely within the water cooled jacket as before. It is seen that the operation of this construction is similar to that of Figures 1 and 2.

While I have shown and described only certain illustrative embodiments of the present invention, it is apparent that further modifications may rise. Therefore, I do not wish to be limited by the disclosure but only by the scope of the appended claims.

50 I claim:

1. In a blast furnace wherein the tuyère jacket is supported on the water cooled jacket that surrounds the hearth, a device for preventing cinder eruptions through the plane of contact between the jackets comprising an annular flange de-

pending from the tuyère jacket and fitting within the water cooled jacket.

2. In a blast furnace having an outer jacket and a water cooled jacket surrounding the brickwork of the hearth, an outwardly extending ledge on the upper edge of said water cooled jacket resting on the upper edge of said outer jacket, and a tuyère jacket resting on said ledge, a device for preventing cinder eruptions through the plane of contact between the jackets comprising an annular flange depending from the underface of said tuyère jacket and fitting closely within said water cooled jacket.

3. In a blast furnace having an outer jacket and a water cooled jacket surrounding the brickwork of the hearth, an outwardly extending ledge on the upper edge of said water cooled jacket resting on the upper edge of said outer jacket, and a tuyère jacket resting on said ledge, the contact between said ledge and said tuyère jacket being imperfect, a device for preventing cinder eruptions through the imperfect contact comprising an annular metal flange depending from the underface of said tuyère jacket and fitting closely within said water cooled jacket, said flange forming a baffle to deflect cinder that escapes through the brickwork into contact with said water cooled jacket.

4. In a blast furnace having an outer jacket and a water cooled jacket surrounding the brickwork of the hearth, an outwardly extending ledge on the upper edge of said water cooled jacket resting on the upper edge of said outer jacket and receiving the cooling water connections to said water cooled jacket, and a tuyère jacket resting on said ledge, the contact between said ledge and said tuyère jacket being imperfect, a device for preventing cinder eruptions through the imperfect contact comprising an annular flange depending from the underface of said tuyère jacket

inwardly of the outer edge and fitting between the outside of the brickwork and the inside of said water cooled jacket closely within the latter, said flange forming a baffle to deflect cinder that escapes through the brickwork into contact with said water cooled jacket beneath the imperfect contact with the tuyère jacket.

5. In a blast furnace having an outer jacket and a water cooled jacket surrounding the brickwork of the hearth, an outwardly extending ledge on the upper edge of said water cooled jacket resting on the upper edge of said outer jacket and receiving the cooling water connections to said water cooled jacket, and a tuyère jacket resting on said ledge, the contact between said ledge and said tuyère jacket being imperfect, a device for preventing cinder eruptions through the imperfect contact comprising an annular flange depending from the underface of said tuyère jacket inwardly of the outer edge and fitting between the outside of the brickwork and the inside of said water cooled jacket, said flange containing a duct for circulation of cooling water connected with the cooling water connections to said water cooled jacket.
